UNITED STATES PATENT OFFICE

HENRY HAMMOCK AND GRANT RIDDLE, OF BOISE, IDAHO

FRUIT-PICKER'S BAG

Application filed January 12, 1928. Serial No. 246,224.

This invention relates to bags for use by fruit pickers, and one of the objects of the invention is to provide a bag which is so constructed that bruising or damage to the fruit 5 is reduced to a minimum.

A further object is to provide very simple means whereby the bottom of the bag may be held in a folded back condition and whereby the folded or returned portion of the bag may 10 be lowered from time to time as the picking progresses, thus acting to further reduce any chance of the fruits being bruised.

Other objects will appear in the course of the following description.

15 Our invention is illustrated in the accompanying drawing, wherein:—

Figure 1 is a perspective view of a fruit picking bag constructed in accordance with our invention;

20 Figure 2 is a vertical section through the bag with the bottom of the bag extended;

Figure 3 is a fragmentary transverse section through the top of the bag;

25 Figure 4 is a perspective view of the bag frame;

Referring to this drawing, 10 designates a bag, which may be made of canvas, duck or any other suitable material, the mouth of the bag being supported by a frame 11, this frame 30 extending across one side of the bag and across the ends thereof and then inward toward the middle of the bag. This frame is enclosed within a hem 12 and the material of the bag is stitched up along the front of the bag, as at 13.

35 It is to be noted that this frame does not extend entirely across the rear wall of the bag and thus the rear wall is flexible and will conform to the contour of the wearer to some extent, thus rendering the bag much more comfortable than if a rigid frame extended across the rear wall which, under the weight of the fruit, would be pressed toward the wearer.

40 Riveted to the front of the bag and to the turned-in ends of the frame 11 are the straps or shoulder bands 14 which are made of several thicknesses of canvas and which are provided with snap hooks 15 at their extremities. These hooks are adapted to engage 45 with rings 16 which are attached by leather

tabs to the frame, these tabs being riveted to the frame by rivets 17. There are three of these rings 16. The bag is open at the bottom but stitched into a fold of the bag at opposite sides thereof are the ropes 18. These ropes 55 are provided with knots 19 at spaced points along their length, and coacting with these knots are the hooks 20 which are riveted or otherwise attached to the ends of the bag as, for instance, by the same rivets that hold the 60 leather tabs in place for the hooks 15.

Disposed within the bag is a canvas baffle 21. The two end edges of the piece of canvas constituting this baffle are so stitched to the sides of the bag that each end edge at its 65 middle is higher than at its ends. Thus the middle of this baffle is higher than the ends of the baffle. Thus the fruit dropped upon the baffle will be directed sometimes to one side of the bag and sometimes to the other 70 side of the bag, thus preventing all of the fruit from being discharged into, say, the middle of the bag and piling up at the middle of the bag instead of being more or less distributed evenly. These ends extend into 75 sufficiently close proximity to the end walls of the bag as to impede the passage of fruit of ordinary size.

The fruit dropping into the bag in this manner is extremely likely to be bruised and this bruising, of course, will materially reduce the value of the fruit on the market, as not only does this bruising render the fruit unattractive, but decay is very liable to start at any bruised point, by checking the 80 passage of the fruit into the bag the impetus of the fruit is reduced. The fruit cannot drop directly into the bag and on the fruit already therein, but drops onto the baffle 21 which checks the speed of the fruit and the fruit then drops merely the distance between the baffle and the top of the fruit already in the bag. This baffle is sewed into the mouth 85 of the bag about six inches from the top and when the picker drops the fruit from above it comes in contact with this baffle, which retards the movement of the fruit enough to prevent damage or bruising, as the fruit cannot fall directly downward against the bottom of the bag but is retarded. This will 90 95 100

tend to prevent the fruit from becoming bruised or damaged, and this damage is further prevented by the adjustability of the bottom of the bag, as heretofore stated. Thus when the picker is starting his pick, he raises the cords or ropes 18 and thus folds the bag so that it is relatively shallow, and engages the lowermost knot 19 with the hook 20. As the bag fills, he disengages the lowermost knots and lowers the bag and engages the next knots with the hook, and so on until the bag is completely filled. When the bag is to be emptied, the ropes are entirely disengaged from the hooks and the fruit can then be emptied into receptacles without removing the bag from the shoulders of the picker.

It will be seen that this construction is a very simple one and that it has been found in practice to be particularly effective in preventing the bruising or injuring of fruit. While the ropes 19 for supporting the folded bag bottom are also effective in reducing blemishing of the fruit, yet they provide a very simple way in which the bag may be held folded or the bag readily released for the discharge of the contents thereof.

We claim:

1. A fruit picking bag having a baffle of textile fabric secured in the mouth of the bag below the top thereof, the baffle inclining downward from its middle toward its ends and said ends being spaced from the body of the bag to permit the passage of fruit over the ends of the baffle.

2. A fruit picking bag having a baffle of textile fabric secured in the mouth of the bag below the top thereof, the baffle inclining downward from its middle toward its ends and said ends being spaced from the body of the bag to permit the passage of fruit over the ends of the baffle, the space being small enough to retard the fruit.

3. A fruit picking bag having a mouth frame and open at its bottom, shoulder straps secured to the frame, a baffle of textile fabric disposed below the frame and attached to the sides of the bag but terminating short of the ends of the bag, said baffle being formed to provide two laterally and downwardly extending channels, hooks projecting from the ends of the frame, and flexible members attached to the bottom of the bag and formed at intervals to engage with said hooks whereby the bottom of the bag may be gradually lowered as the bag becomes filled.

4. A fruit picking bag having a rectangular mouth frame extending across the front and the ends of the bag and inward across the rear of the bag adjacent the ends thereof, rings operatively secured to the frame at the sides of the bag and shoulder straps each attached to the rear face of the bag, the straps being adapted to extend diagonally across each other and the extremities of the straps

being provided with snap hooks for engagement in the rings.

In testimony whereof we hereunto affix our signatures.

HENRY HAMMOCK.
GRANT RIDDLE.
